GASKET

Leonard H. Darbyshire, Detroit, Mich., assignor
to Norge Corporation, Detroit, Mich., a corpora-
tion of Michigan

Application August 8, 1932, Serial No. 627,865

2 Claims. (Cl. 20—69)

This invention relates to freezer construction for mechanical refrigerators and has special reference to the elimination of air circulation into the quick freezing compartment used for the production of ice cubes and frozen desserts.

I have found that when air circulation is permitted into the quick freezing compartment that frost is deposited on the walls and containers therein causing the containers to stick and prevent easy removal thereof. The air circulation also carries food odors into the compartment to contaminate the water or delicate confections being frozen with unpalatable foreign flavors. It has been heretofore proposed to use a door over the end of the compartment but even that is insufficient to prevent deposition of frost around the mouth of the compartment due to the extreme low temperatures maintained therein which serves to condense the moisture in the air attracted to the low temperature area. I have discovered that it requires the provision of a highly efficient air seal to eliminate such condensation and frosting so that it is an object of this invention to provide such a seal.

It is another object of this invention to provide an air seal or gasket that can be applied to the shell of the quick freezing compartment and that will be yieldingly interposed between the end of the shell and a spring closed door.

It is a further object of this invention to provide an elastic gasket engaging both the periphery and edge of an open ended compartment whereby to maintain the gasket in position.

It is another object of this invention to provide a simple and inexpensive form of gasket easily applied to the entrance end of a compartment.

Other and further important objects of this invention will be apparent from the disclosures in the specification and the accompanying drawing.

This invention (in a preferred form) is illustrated in the drawing and hereinafter more fully described.

On the drawing:

Figure 1 is a fragmentary front view of an open refrigerator showing the shield and door covering the freezing unit and ice tray receptacle or sleeve;

Figure 2 is a fragmentary perspective view of the front end of the freezer sleeve with a gasket applied thereto embodying one form of this invention;

Figure 3 is an enlarged section on the line III—III of Fig. 2, adding the door thereto; and

Figure 4 is a section similar to Fig. 3, embodying a modified form of gasket.

As shown on the drawing:

The top portion of an opened refrigerator compartment 10 is shown in Figure 1 to illustrate the location of a freezer unit behind a shield 11 apertured for entry to the open end of a freezer sleeve 12 into which trays are inserted to produce ice cubes or frozen confections. The shield aperture is closed by a door 13 normally held shut by spring hinges 14.

The freezer sleeve 12 is formed as rectangular 10 in section to accommodate a stack of ice trays and may be slightly enlarged to form a shoulder 15 back of the open end 16 to facilitate access to and removal of selected trays. It may also be advantageous to roll back the edge of the entrance end as shown at 17 in Fig. 3, although if desired the end may be arranged otherwise as for example flared as at 18 in Fig. 4.

An endless gasket ring of resilient or elastic material 19 is shaped to conform to the profile of 20 the enlarged part of the shell, with a front bead portion 20 overlapping the edge of the opening and a rear portion 21 seating behind the shoulder formed by the enlarged part of the shell. The ring is stretched to snap over the shell, the 25 stretching causing a tension in cross section which causes the front and rear portions to snugly fit the corresponding parts of the shell to retain the gasket in place, the front bead 20 serving as a bumper and seal against the inner surface of the 30 door. It is desirable to slightly undercut the front bead to form a reentrant inner surface 22 for the lip 23 of the bumper.

While I have described the preferred form of gasket shown in Figure 3 as made of resilient or 35 elastic material I desire to have it understood that I do not desire to limit myself to the use of solid live rubber, since other materials may be utilized to support the front bead forming the bumper and gasket seal.

A modified form of gasket construction as shown in Fig. 4 comprises a bead 24 adapted to engage over the flared end of the shell, an inner clip 25 holding the bead in place.

It will thus be seen that I have invented an improved closure sealing gasket particularly adapted for use in sealing the quick freezing compartment from contaminating air circulation and in the prevention of frosting and sticking of the trays inserted therein, my sealing gasket being 50 adapted to retain its effective position without interfering with the insertion or removal of the trays.

I am aware that many changes may be made and numerous details of construction may be 55

varied through a wide range without departing from the principles of this invention, and I, therefore, do not purpose limiting the patent granted hereon otherwise than necessitated by the prior art.

5 I claim as my invention:

1. As an article of manufacture an endless resilient sealing strip adapted to envelop opposed shoulders of a peripheral enlargement adjacent the open end of a shell, comprising a resilient gasket adapted to embrace the exterior of the shell and envelop the opposed shoulders and carrying a bead overhanging the edge of the shell for engagement between the edge of the shell and a closure therefor, said resilient gasket being adapted to be stretched when in position whereby the resulting transverse contraction grips the
- 10
- 15

shoulders of each enlargement to firmly retain the gasket in position.

2. As an article of manufacture an endless resilient sealing strip adapted to envelop opposed shoulders of a peripheral enlargement adjacent the open end of a shell, one shoulder being formed by the edge of said shell, comprising a resilient gasket adapted to embrace the exterior of the shell and envelop the opposed shoulders and carrying a bead overhanging the edge of the shell for engagement between the edge of the shell and a closure therefor, said resilient gasket being adapted to be stretched when in position whereby the resulting transverse contraction grips the shoulders of each enlargement to firmly retain the gasket in position. 10 15
